UNITED STATES PATENT OFFICE

WESLEY J. SHAW, OF HAVERHILL, MASSACHUSETTS, ASSIGNOR TO NEW ENGLAND WOOD HEEL CO., OF HAVERHILL, MASSACHUSETTS, A CORPORATION OF MASSACHUSETTS

MACHINE FOR GROOVING WOOD HEELS

Application filed November 28, 1927. Serial No. 236,153.

The present invention relates to machines for grooving the breasts of wood-heel blocks, and more particularly Cuban-heel blocks.

The term "Cuban" will be used in the specification and claims to denote heels of the type herein described; and as distinguished from "Louis" or "French" heels. The heels known in the trade as "military" heels, for example, will be included herein in the designation "Cuban."

The breasts of Louis-heel blocks have been grooved by machinery for many years. The blocks are placed, heel-seat down, upon a carrier which carries them past a breast-grooving cutter. The cutter is so shaped, and the path of travel of the blocks past the cutter is such, that the resulting groove in the breast is transversely curved in cross section from the heel seat to the tread.

The corresponding cross sectional curve of a Cuban heel extends, however, from side to side of the heel, in a direction at right angles to that from seat to tread. In order to groove the breasts of Cuban-heel blocks, therefore, it is impossible or impracticable to use the automatic machinery designed for breasting Louis heels. The difficulties connected with the automatic grooving of Cuban heels have no counterpart in the breasting of Louis heels and, so far as known, no one, prior to the present invention, has ever succeeded in building a satisfactory machine for performing this operation. Cuban heels are still grooved slowly and laboriously with hand-operated tools.

It is therefore an object of the present invention to provide automatic machinery of novel character for grooving Cuban-heel blocks. Other objects will be explained hereinafter and will be particularly pointed out in the appended claims.

The invention will now be described in connection with the accompanying drawings, in which Fig. 1 is a diagrammatic view, in front elevation, illustrating one embodiment of the invention, a part being broken away for clearness; Fig. 2 is a plan of the same, with parts omitted for clearness; Fig. 3 is a plan of a detail, shown enlarged with respect to Figs. 1 and 2; Fig. 4 is a similarly enlarged

section, taken upon the line 4—4 of Fig. 3, looking in the direction of the arrows; and Fig. 5 is a perspective view of a Cuban-wood-heel block.

Cuban-heel blocks, before they are operated upon in the illustrative machine, have the shape indicated in Fig. 5 by full lines. The tread portion of the heel block is shown at 1 and the heel-seat portion at 3. The breast 5 is bounded by the tread and the heel-seat portions 1 and 3 and the side faces 7 and 9. The face 11 opposite to the breast 5 inclines upward from the tread portion 1 to the heel-seat portion 3.

Blocks of this shape are placed upon an endless carrier, with the side face 9 resting upon the carrier, and with the breast portion 5 disposed at one side; and are advanced by the carrier to a rotating grooving cutter 8, by which the breast portions 5 of the blocks are successively cut longitudinally along the dot-and-dash lines 10, shown in Fig. 5, from the tread 1 to the seat 3. The cut 10 may, if preferred, be effected in two stages, the second stage of the cut being effected by a second cutter 12 of larger diameter.

The endless carrier 6 comprises a plurality of links 16 connected by pintles 18 that are adapted to be engaged by teeth 20 of a driving wheel 22 over which the carrier 6 is mounted. The driving wheel 22 may be driven from any desired source of power (not shown). The driving wheel 22 is shown in Fig. 1 at the left-hand end of the machine. The carrier 6 is mounted also over an idler wheel 24 at the right-hand end of the machine. The idler wheel 24 is provided with a circular periphery and with flanges 26 between which the links of the carrier 6 are confined. The periphery of the driving wheel 22, however, is flat-sided, as shown more particularly in Fig. 1, in order that the links 16 may rest snugly against the sides thereof while the teeth 20 engage the pintles 18 to drive the carrier 6. The carrier travels on substantially straight tracks 28 and 30 (Fig. 4) located at the sides of an opening 32 in the frame of the machine, over which opening the carrier is suspended. This construction involves less friction than if the

95

100

carrier dragged over a solid bed bottom. The substantially straight tracks 28 and 30 ensure that the portion of the path of travel of the carrier between the driving wheel 22 and the idler wheel 24 shall be substantially straight. In order to prevent vibration of the carrier during its travel, it is confined on one side between the track 28 and a ledge 34, and on the other side between the track 30 and a ledge 36. The ledges 34 and 36 may be secured to the frame of the machine in any desired manner, as by means of screws 37, Fig. 4.

The blocks are successively placed upon the carrier 6 at A, with the breast portion 5 projecting at one side of the carrier. As each block is advanced forward toward the cutters, its breast 5 engages an alining face 39 of an alining gage 41 which, positioned at one side of the path of travel of the jaws, pushes the block transversely across the carrier, into proper position to be engaged by the cutters. In this position, the breast 5 of the block extends slightly sidewise beyond the carrier in the range of action of the cutter 8. While being so pushed, the tread 1 of the block slides along a jaw 38 that is mounted upon a link of the carrier so as to move therewith. The plane of the jaw 38 is substantially at right angles to the path of travel of the link 16, so that the tread 1 of the block may engage the jaw 38 snugly when resting longitudinally of the carrier, as illustrated more particularly in Fig. 3, and as herein-after more fully described. The block then travels under a clamping jaw 40. The forward beveled part 45 of the jaw 40 first forces the tread 1 of the block into firm engagement with the jaw 38, after which the remainder of the jaw clamps the block tightly against the corresponding link 16 of the carrier. The clamping effect is thus obtained after the block has first become properly positioned against the jaw 38, but before it has been advanced to the cutter 8. At the time that the breast 5 of the block is presented to the cutter, therefore, it is firmly clamped between its side faces 7 and 9 and its tread 1 is engaged snugly against the jaw 38, the cutter acting at a point intermediate between the carrier 6 below and the jaw 40 above, and to one side of the carrier 6 and the jaw 40. Unless the block is thus firmly clamped, with the block resting snugly on the carrier, the groove 10 will not be accurately positioned in the block. As blocks of ostensibly the same size and shape are not uniform in width, from the face 7 to the face 9, moreover, the jaw 40 is caused, by a stiff coil spring 118, to press down upon the face 7 with a spring-pressed or other yielding, though severe, clamping action. Blocks of considerably varying width are, in that manner, clamped with equal effectiveness.

In order to bring this result about effec-

tively, the jaw 40 is intermediately pivoted at 114 upon a plunger 116 that is vertically yieldable, in opposition to the action of the spring 118, in a framework 120 that is vertically adjustable by means of a handwheel 122. Transverse adjustment may be effected by means of a hand-wheel 124 that is adapted to control the transverse adjustment of a slide 126 that carries the framework 120.

The pivotal movement of the jaw 40 about its intermediate pivotal point 114 is yieldingly resisted by two coil springs 128 and 130 mounted between the framework 120 and the jaw 40 on each side of the pivot. When a block is forced under the jaw 40, the spring 128 is first compressed. The spring 130 is compressed later, as the block is advanced beyond the jaw 40. The spring 118 is called into play for blocks of extra thickness.

The position of the groove 10 upon the block 2 will depend upon the height of the cutters 8 and 12. These should be situated substantially in the plane of movement, and to one side of the path of travel of the jaws 38, or slightly above the links 16, at intermediate positions of the carrier 6, as illustrated more particularly in Fig. 1. The cutters are mounted upon spindles 86 that rotate in bearings 88 and 90 and that are driven by motors or pulleys 92. The spindles 86, bearings 88 and 90 and motors or pulleys 92 are mounted as a unit upon vertically adjustable plates 94. The plates 94 may be secured in vertically adjusted position by bolts 98 extending through elongated openings 100. The vertical adjustment may be facilitated by hand wheels 102 secured to threaded stems 104 that extend through lugs 106 in the frame of the machine and that engage the plates 94.

The jaw 40 may extend throughout such a length of the machine as to maintain the block clamped until after it has traveled past the second cutter 12 also, or a separate clamping jaw 141 may be provided which may, if desired, and as is illustrated, be similar to the jaw 40. After the block has passed the cutter 12, it is released and may be removed from the machine in any desired manner.

Though Cuban-heel blocks are of the general shape heretofore described, they vary somewhat in size and in the inclination or angle of the breast 5 to the tread 1 and heel-seat portion 3. In this respect, among others, the breasting by machinery of Cuban-heel blocks presents problems that are not existent in the case of Louis heels; for it becomes necessary to provide a different jaw 38 for practically every different shape and size of heel block. According to a feature of the present invention, however, it is possible to use one jaw 38 for all sizes and shapes of Cuban-heel blocks that are used in actual practice, merely by providing a suitable adjustment for the jaw 38.

As the jaws 38 are substantially alike, it

will suffice to describe one jaw 38 only. The jaw 38 is pivoted upon its link 16 at one end 42 so as to adapt it to take up different angular positions upon the link. The other end of the jaw is provided with a circular slot 44. A bolt 46 extends through the slot 44 and into the link 16 to clamp the jaw in pivotally adjusted position.

In order to provide for rapid adjustment of all the jaws, a gage 48 is positioned as illustrated more particularly in Figs. 2 and 3. The gage is adjustable transversely of the carrier to positions that may be determined in advance to correspond to desired angular positions of the jaws 38. A scale may be provided to help set the gage in predetermined transversely adjusted position.

The bolts 46 are first loosened successively if necessary, and the jaws are moved about their pivots 42 to an extreme limit of movement. The gage 48 is adjusted to the predetermined setting, and the carrier is then started to move slowly. As the successive links travel past the gage 48, the jaws 38 are engaged thereby and are thus moved to a position of angular adjustment corresponding to the predetermined adjustment of the gage. The bolts 46 are then retightened to secure the jaws firmly in adjusted position.

Unless this operation is carefully carried out, there will be danger of the jaws being moved by the gage 48 too far beyond the desired position of adjustment. A finger 50 (shown in Fig. 4 as a ball) is therefore provided in each link 16. Each ball finger 50 is spring-pressed upward into engagement with the bottom face of the jaw 38. This bottom face is provided with a plurality of circularly arranged recesses 52 into which the spring-pressed ball fingers 50 are adapted to enter. As the spring fingers 50 tend easily to enter the recesses 52, but tend to leave the recesses only upon the exertion of a somewhat greater force, the angular position of the jaw 38 becomes relatively fixed. If, therefore, the gage 48 is properly adjusted, it will move the jaw 38 to a position such that a ball finger 50 will drop into one of the openings 52, and the jaw will be held in that position until the bolt 46 is retightened. As a single circular row of openings 52 will not provide a sufficient range of adjustment, several such rows, with spring-pressed ball fingers 50 for each row, are provided, as illustrated.

Modifications may be made within the spirit and scope of the invention, as will readily occur to persons skilled in the art. It will therefore be understood that the machine illustrated and described herein is illustrative only, and that the invention is not restricted thereto, but is defined by the appended claims.

What is claimed is:

1. A machine for grooving the breasts of Cuban-heel blocks in a longitudinal direction, the said machine having, in combination,

heel-block-grooving cutter, an endless carrier comprising a plurality of links, a jaw mounted upon each link of the carrier so as to move with the carrier and extending substantially at right angles to the path of travel of the jaw so as to be engaged by an end of a Cuban-heel block when resting longitudinally on the carrier with the breast extending sidewise beyond the jaw at one side of the carrier, a gage situated at one side of the path of travel of the jaws and adapted to be engaged by the breast of the heel block to cause the block to be positioned on the carrier in engagement with the jaw in predetermined relation to the cutter, the jaw being angularly adjustable on the link so as to correspond to the breast angle of different heel blocks, means operable during the actuation of the carrier to clamp the block on the carrier in the said predetermined relation to the cutter, and means for actuating the carrier, the cutter being situated at one side of the path of travel of the jaws, whereby the carrier is adapted to advance to the cutter clamped Cuban-heel blocks in position such that the cutter shall cut a groove in the breast of each heel block in a longitudinal direction.

2. A machine for grooving the breasts of Cuban-heel blocks in a longitudinal direction, the said machine having, in combination, a heel-block-grooving cutter, an endless carrier comprising a plurality of links, a jaw mounted upon each link of the carrier so as to move with the carrier and extending substantially at right angles to the path of travel of the jaw so as to be engaged by an end of a Cuban-heel block when resting longitudinally on the carrier with the breast extending sidewise beyond the jaw at one side of the carrier, a gage situated at one side of the path of travel of the jaws and adapted to be engaged by the breast of the heel block to cause the block to be positioned on the carrier in engagement with the jaw in predetermined relation to the cutter, means operable during the actuation of the carrier to clamp the block on the carrier in the said predetermined relation to the cutter, and means for actuating the carrier, the cutter being situated at one side of the path of travel of the jaws, whereby the carrier is adapted to advance to the cutter clamped Cuban-heel blocks in position such that the cutter shall cut a groove in the breast of each heel block in a longitudinal direction.

3. A machine for grooving the breasts of Cuban-heel blocks in a longitudinal direction, the said machine having, in combination, a heel-block grooving cutter, an endless carrier comprising a plurality of jaws each adapted to be engaged by an end of a Cuban-heel block when resting longitudinally on the carrier in predetermined relation to the cutter, the jaws being angularly adjustable on the carrier so as to correspond to the breast angle of different heel blocks, means operable

during the actuation of the carrier to clamp the block on the carrier in the said predetermined relation to the cutter, and means for actuating the carrier, whereby the carrier is adapted to advance to the cutter clamped Cuban-heel blocks in position such that the cutter shall cut a groove in the breast of each heel block in a longitudinal direction.

4. A machine for grooving the breasts of Cuban-heel blocks in a longitudinal direction, the said machine having, in combination, a heel-block-grooving cutter, an endless carrier comprising a plurality of jaws each adapted to be engaged by an end of a Cuban-heel block when resting longitudinally on the carrier in predetermined relation to the cutter, means operable during the actuation of the carrier to clamp the block on the carrier in the said predetermined relation to the cutter, means for actuating the carrier, whereby the carrier is adapted to advance to the cutter clamped Cuban-heel blocks in position such that the cutter shall cut a groove in the breast of each heel block in a longitudinal direction, and means operable at a predetermined position in the path of travel of the carrier for angularly adjusting the jaws to correspond to the breast angle of different heel blocks.

5. A machine for grooving the breasts of Cuban-heel blocks in a longitudinal direction, the said machine having, in combination, a heel-block-grooving cutter, an endless carrier comprising a plurality of jaws each adapted to be engaged by an end of a Cuban-heel block when resting longitudinally on the carrier in predetermined relation to the cutter, means operable during the actuation of the carrier to clamp the block on the carrier in the said predetermined relation to the cutter, means for actuating the carrier, whereby the carrier is adapted to advance to the cutter clamped Cuban-heel blocks in position such that the cutter shall cut a groove in the breast of each heel block in a longitudinal direction, and an adjustable gage positioned at a predetermined position in the path of travel of the carrier for angularly adjusting the jaws to correspond to the breast angle of different heel blocks.

6. A machine for grooving the breasts of Cuban-heel blocks in a longitudinal direction, the said machine having, in combination, a heel-block-grooving cutter, an endless carrier comprising a plurality of jaws each adapted to be engaged by an end of a Cuban-heel block when resting longitudinally on the carrier in predetermined relation to the cutter, means operable during the actuation of the carrier to clamp the block on the carrier in the said predetermined relation to the cutter, means for actuating the carrier, whereby the carrier is adapted to advance to the cutter clamped Cuban-heel blocks in position such that the cutter shall cut a groove in the breast of each heel block in a longitudinal direction.

each heel block in a longitudinal direction, means operable at a predetermined position in the path of travel of the carrier for angularly adjusting the jaws to correspond to the breast angle of different heel blocks, and means for relatively fixing the angularly adjusted positions of the jaws.

7. A machine for grooving the breasts of Cuban-heel blocks in a longitudinal direction, the said machine having, in combination, a heel-block-grooving cutter, a carrier, jaws mounted upon the carrier so as to travel with the carrier, each jaw being adapted to be engaged by an end of a Cuban-heel block when resting longitudinally on the carrier with the breast extending sidewise beyond the jaw at one side of the carrier, the jaws being angularly adjustable on the carrier so as to correspond to the breast angle of different heel blocks, means operable during the actuation of the carrier to clamp the block on the carrier in predetermined relation to the cutter, the cutter being situated at one side of the path of travel of the jaws, whereby the carrier is adapted to advance to the cutter clamped Cuban-heel blocks in position such that the cutter shall cut a groove in the breast of each heel block in a longitudinal direction.

8. A machine for grooving the breasts of Cuban-heel blocks in a longitudinal direction, the said machine having, in combination, a heel-block-grooving cutter, an endless carrier comprising a plurality of links, jaws mounted upon the carrier so as to move with the carrier, each jaw being adapted to be engaged by an end of a Cuban-heel block when resting longitudinally on the carrier with the breast extending sidewise beyond the jaw at one side of the carrier, a gage situated at one side of the path of travel of the jaws and adapted to be engaged by the breast of the heel block to cause the block to be positioned on the carrier in engagement with the jaw in predetermined relation to the cutter, and means for actuating the carrier, the cutter being situated at one side of the path of travel of the jaws, whereby the carrier is adapted to advance to the cutter clamped Cuban-heel blocks in position such that the cutter shall cut a groove in the breast of each heel block in a longitudinal direction.

9. A machine for grooving the breasts of Cuban-heel blocks in a longitudinal direction, the said machine having, in combination, a heel-block grooving cutter, an endless carrier comprising a plurality of links, jaws mounted upon the carrier, so as to move with the carrier, each jaw being adapted to be engaged by an end of a Cuban-heel block when resting longitudinally on the carrier in predetermined relation to the cutter, the jaws being angularly adjustable on the carrier so as to correspond to the breast angle of different heel blocks, and means for actuating

the carrier, whereby the carrier is adapted to advance to the cutter clamped Cuban-heel blocks in position such that the cutter shall cut a groove in the breast of each heel block in a longitudinal direction.

5 10. A machine for grooving the breasts of Cuban-heel blocks in a longitudinal direction, the said machine having, in combination, a heel-block-grooving cutter, a carrier comprising a plurality of jaws each adapted to be engaged by an end of a Cuban-heel block when resting longitudinally on the carrier in predetermined relation to the cutter, means for actuating the carrier, whereby the carrier is adapted to advance to the cutter clamped Cuban-heel blocks in position such that the cutter shall cut a groove in the breast of each heel block in a longitudinal direction, and means operable at a predetermined position in the path of travel of the carrier for angularly adjusting the jaws to correspond to the breast angle of different heel blocks.

15 20 25 In testimony whereof, I have hereunto subscribed my name.
